United States Patent

Des. 235,279

Patented June 3, 1975

235,279

STERILIZER CONTROL INDICATOR

Seymour Schuman, and Arthur W. Kelson, New York,
N.Y., assignors to Proper Manufacturing Co., Inc.,
Long Island City, N.Y.

Filed June 28, 1973, Ser. No. 374,358

Term of patent 14 years

Int. Cl. D24—99

U.S. Cl. D83—1 W

FIG. 2

FIG. 1

FIG. 3

FIG. 1 is a front view of a sterilizer control indicator;
FIG. 2 is a side view thereof;
FIG. 3 is a cross sectional view taken along line 3—3
in FIG. 1 showing the sterilization sensitive material
deposited on an insert backing.

We claim:

The ornamental design for a sterilizer control indicator, as shown and described.
